UNITED STATES PATENT OFFICE.

LE ROY ARMITAGE, OF EAST ORANGE, NEW JERSEY.

ELECTRIC-LAMP FIXTURE.

1,394,529.

Specification of Letters Patent. Patented Oct. 25, 1921.

Application filed May 24, 1920. Serial No. 383,713.

To all whom it may concern:

Be it known that I, LE ROY ARMITAGE, a citizen of the United States of America, residing at East Orange, New Jersey, have invented a new and useful Electric-Lamp Fixture, of which the following is a specification.

My invention relates particularly to an adjustable fixture for incandescent lamps.

10 The main object is to provide a simple and inexpensive construction which is light and compact and can be readily adjusted to many positions, so that it is convenient for use.

15 In the preferred form the invention contemplates the use of a main rod or tube with a special adjustable clamp on one end and an adjustable lamp socket bracket on the other end.

20 Figure 1 shows in full lines one form of device embodying the improvements of my invention, and shows in dotted lines positions of the parts in various adjusted relations;

25 Fig. 2 is a plan view in section, on the plane of the line 2—2 of Fig. 1, showing one of the clamp members with part of its covering broken away;

30 Fig. 3 is a plan in section on the plane of the line 3—3 of Fig. 1, showing the connection of the lamp bracket clamp with the main post; and

Fig. 4 is an end view of the lamp bracket portion with a separate reflector.

35 The main post or standard 5 is preferably cylindrical and tubular, and affords a conduit for the lamp cord 6.

40 The clamp for supporting the device from a book, table or other support has two arms or jaws 7 and 8. The first may be rigidly secured to one end of the post 5, although it may be resilient. The other arm 8 preferably has an opening only slightly larger than the outer diameter of the post 5, and is preferably bent into the form shown in

45 Fig. 1, to facilitate attachment to a suitable support. This jaw 8 is also preferably a resilient or spring jaw and has connected to it a spring jaw 9, which has an opening for the post 5. This jaw 9 is connected to the 50 jaw 8 by a U-shaped portion 10, and the connection may either be integral, welded or riveted, as at 11.

To tighten the jaw 8 down against a support it is simply necessary to push down on 55 the jaw 9. To release the jaw 8 it is necessary to compress the jaw 9, for instance, by

grasping the parts 9 and 8 between the thumb and forefinger. It should also be understood that the jaw 8 may be released from the support by simply swinging the jaw 80 around the post 5.

To prevent scratching and effect a substantial connection of the device with its support, I prefer to cover the jaws 7 and 8 with 65 felt, as at 12.

The bulb 14 may be of any suitable type, carried by any suitable form of socket 15, such as a key or keyless or push-button socket. Preferably a reflector 16 is provided, and this reflector may be either in the 70 form of a silvered coating attached to the bulb, as shown in Fig. 1, or in the form of a separate reflector 16', as shown in Fig. 4.

A clamp 17 has jaws which frictionally engage the post 5, so that the clamp may be 75 slid along the post or rotated about it. This clamp 17 is connected to the socket 15, for instance, by means of a member 18. This member 18 may be pivoted or riveted at 19 to the support 17 so as to hold the parts in 80 their proper relative positions. The base of the member 18 may be loosely mounted between the sides of the clamp 17, so as to permit tilting on the axis of the member 19, if desired. The socket 15 may be rotatably 85 supported by the member 18 through the medium of the bushing 20, so as to facilitate adjustment of the lamp and its reflector 16, if desired. It should be understood that the clamp 17 may be slid up and down on the 90 post 5 or rotated on the post 5, so as to bring the bulb into the desired position.

It will be seen that the post 5 constitutes a handle by which the entire device may be held and adjusted. By making this post 95 hollow or tubular it may also be utilized as a guard for the cable or lamp cord, so as to keep it out of the way of the parts of the clamps, but without interfering with the various adjustments of the device.

100 It will also be seen that the direction of projection of the light rays may be altered as desired, in view of the fact that the reflector is adjusted about the axis of the socket, and that the socket is adjustable up and down 105 the post, as well as around the axis of the post. The construction thus affords in compact space a substantial universal adjustment.

I claim:

110 1. An electric lamp fixture comprising a post, a jaw fixed to said post, a second jaw

- having a spring arm portion, said second jaw and its spring arm portion having openings slidably receiving said post, and a lamp socket adjustably carried by said post.
5. 2. An electric lamp fixture comprising a post, and a supporting clamp having a pair of jaws, one of said jaws having a part embracing said post and having a resiliently pressed portion embracing said post for gripping the latter and holding said last-mentioned jaw in position on said post.
10. 3. An electric lamp fixture comprising a post, a supporting clamp having two jaws, one of which is fixed to the post and the other of which is slidably mounted on said post, said slidable jaw having a spring jaw of substantially U-shape and having a part embracing said post, said spring jaw when released serving to grip the post and hold said slidable jaw in position on the post, and means for adjustably supporting a lamp on said post.

LE ROY ARMITAGE.
